(57) **CLAIM**

The ornamental design for a seedling transplanting device, as shown and described.

DESCRIPTION

FIG. 1 is a perspective view of a seedling transplanting device showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view thereof, showing the seedling transplanting device in its contracted state;

FIG. 9 is a perspective view thereof, showing one lower part of the seedling transplanting device rotated;

FIG. 10 is a perspective view thereof, showing the other lower part of the seedling transplanting device rotated; and, FIG. 11 is a perspective view thereof with an element held by the lower parts of the seedling transplanting device.

The broken lines illustrate portions of the seedling transplanting device that form no part of the claimed design. The broken lines showing an element in FIG. 11 are for the purpose of illustrating environmental structure, and form no part of the claimed design.
